US00D994950S

(12) **United States Design Patent** (10) Patent No.: **US D994,950 S**
(45) Date of Patent: **** Aug. 8, 2023**

(54) **LED LAMP**

- (71) Applicant: **SHENZHEN SNC OPTO ELECTRONIC CO., LTD**, Shenzhen (CN)
- (72) Inventor: **Nianhua Pan**, Shenzhen (CN)
- (73) Assignee: **SHENZHEN SNC OPTO ELECTRONIC CO., LTD**, Shenzhen (CN)

(**) Term: **15 Years**

(21) Appl. No.: **29/753,132**

(22) Filed: **Sep. 30, 2020**

(30) **Foreign Application Priority Data**

(57) **CLAIM**

The ornamental design for an LED lamp, as shown and described.

DESCRIPTION

FIG. 1 is a perspective view of an LED lamp showing my new design;

FIG. 2 is another perspective view of the LED lamp shown in FIG. 1;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the LED lamp that form no part of the claimed design.

1 Claim, 8 Drawing Sheets
